UNITED STATES PATENT OFFICE.

HORTON H. HOBBS, OF ALACHUA, FLORIDA.

LOCK FOR AIR VALVES.

Application filed September 16, 1924. Serial No. 738,042.

To all whom it may concern:

Be it known that I, HORTON H. HOBBS, a citizen of the United States, residing at Alachua, in the county of Alachua and 5 State of Florida, have invented certain new and useful Improvements in Locks for Air Valves, of which the following is a specification.

This invention relates to locks for preventing the unauthorized use of motor cars by admitting air to the cylinders of their motors through suitable valves, so that the motors cannot be operated until such valves are closed; and it consists in the novel construction and combination of the parts hereinafter fully described and claimed whereby the air valve is locked when opened so that it can only be unlocked by a person having the combination necessary to 20 operate the lock.

In the drawings, Figure 1 is a vertical section through an air valve provided with a combination lock according to this invention. Fig. 2 is a cross-section, from 25 above, taken on the line 2—2 in Fig. 1. Fig. 3 is a cross-section, from above, taken on the line 3—3 in Fig. 1. Fig. 4 is a plan view of the three disks on the valve stem. Fig. 5 is a plan view of one washer. 30 The valve is provided with a cylindrical casing 6 having one or more perforations 7 for admitting air. A valve seat 8 is provided at the bottom of the casing, and 9 is an air pipe below the valve seat. The 35 other end of the air pipe 9 is connected to the inlet manifold of the motor between its carburetor and cylinders, or to any other suitable point, so that air admitted through the valve and air pipe will prevent the 40 motor from being operated to drive the car or automobile in the usual manner. The upper end of the valve casing is closed by a cover 10 which is permanently secured to it in any approved way. The cover can 45 be secured by screws 12 the ends of which are riveted over.

The casing, cover and air pipe are preferably formed of very hard metal, such as steel, so that they cannot be opened or sawed 50 off. The air pipe can be welded or brazed to the casing and to the manifold.

A valve stem 14 is provided and has a screwthreaded portion 15 which works in a screwthreaded hole in the cover 10, and 55 this stem has also a disk valve 16 secured to it for closing the valve seat 8. The

lower end portion 17 of the valve stem is tubular, and works over a stationary guide spindle 18 which is secured to the casing or air pipe concentric with the valve seat. 60 This spindle guides the valve onto its seat, and permits the valve stem to work freely in the cover.

The upper part of the casing is provided with a longitudinal stop rib 20. The middle part of the casing is provided with a sleeve or internal projection 21 having a series of longitudinal grooves 22, preferably twelve, spaced at equal distances apart around it, and having their bottoms arranged in a circle which intersects the stop rib 20. Three of the grooves 22 extend all the way through the projection, and three others only extend about half way through the projection 21 for their full 70 depth, their lower end portions being formed of shallow grooves 24 of about one-half the depth of the grooves 22, but otherwise similar to them. The remaining grooves 22 only extend about half way through the projection 21, so that their lower ends are closed by stops 23. The valve stem 14 is provided with any suitable handle 25 for revolving it, and is extended to any point convenient to the person who drives the 80 car. The grooves 24 are hereinafter referred to as shallow grooves, and all the other grooves are referred to as deep grooves, irrespective of their length. The deep 85 grooves closed by the stops 23 and the deep 90 grooves in line with the shallow grooves 24 are shorter than the deep grooves which extend continuously from one end to the other of the sleeve or projection 21.

The valve stem 14 has three disks 28, 29 and 30 mounted on it, and 31 are cupped spring washers arranged on the stem between the adjacent disks. A stop shoulder or nut 32 is provided on the stem for the top disk 28 to bear against, and a helical spring 33 is interposed between the bottom disk 30 and the valve which is secured on the stem by a nut 34. The disks are held in frictional engagement with the stem by the washers and spring so that they revolve 100 with the stem when not obstructed. Each disk has a long radial lug 35 on its periphery and a shorter lug 36. The short lug 36 of the middle disk is arranged diametrically opposite to the long lug 35, and the short lugs of the upper and lower disks are arranged at a right angle with their 105 110

long lugs but so as to project in opposite directions. When all three long lugs are arranged directly in line with and one above another the short lugs are all out of line with each other.

When the valve is closed the motor operates in the usual way. When the driver leaves the car he opens the valve by revolving and sliding the valve stem so that all the 10 disks are raised above the sleeve or projection 21. He revolves the stem 17 until the screwthreaded part 15 is clear of the cover 10, and then slides the stem outwardly to a sufficient extent. The closing of the air 15 valve can only be effected by one who knows the correct combination. In order to close the valve the three long lugs 35 are placed in line by contact with the stop rib 20. This permits the long lugs to pass down- 20 wardly through any one of the continuous grooves, but not through the closed grooves or through the shallow grooves. The stem is revolved in a certain way to permit the short lugs 36 to pass downwardly through 25 the shallow grooves, so that ultimately, the correct combination having been worked, all the disks are moved down to a sufficient extent, and the air valve is screwed down onto its seat. In the example shown, when the 30 stem 17 is revolved clockwise and the long lugs 35 are placed in line by contact with the stop 20, the three short lugs are out of line with each other, as will be seen by Fig. 4. The long lug 35 of the bottom disk 35 can now go down the deep groove 22 at 35 the left hand in Fig. 3, and its short lug 36 can go down the shallow groove at the top of Fig. 3. The stem 17 must now be re- 40 volved to turn the middle disk 29 until its long lug 35 comes over the deep groove at the left in Fig. 3 below the groove 22. The short lug 36 of disk 29 now comes over the 45 shallow groove 24, diametrically opposite the deep groove, and the disk 29 can be pushed down. The stem 17 must now be re- 50 volved until the long lug 35 of the top disk 28 comes over the deep groove 22 at the right in Fig. 3, and its short lug 36 comes over the shallow groove at the right in Fig. 3. The top disk can now be pushed down, and 55 the screw 15 can be screwed into the screwthreaded hole in the cover until the valve is screwed down onto its seat. The locking mechanism on the casing and valve stem is always ready for use, as no key is required, and nothing has to be set or arranged before the valve is operated.

The washers 31 are preferably splined to the valve stem, and a separate nut 38 is provided for adjusting the spring 33. The valve 16 is secured loosely on its stem by the nut 34, so that it will adjust itself to its seat when closed. The valve can be opened without working the combination, as the 60 disks do not descend out of engagement

with the slots or below the end of the projection 21.

What I claim is:

1. The combination, with a casing having a valve seat at one end, of a revoluble valve 70 stem provided with a valve for closing the valve seat and having also means for moving it longitudinally in the casing, and a locking mechanism inclosed in the said casing and carried by it and the valve stem and operating to prevent the unauthorized use of the valve.

2. The combination, with a casing having a valve seat at one end, of a revoluble valve 80 stem provided with a tubular end portion and a valve for closing the valve seat, said stem having also means for moving it longitudinally of the casing, a guide spindle secured to the casing concentric with the valve seat and projecting into the tubular portion of the valve stem, and a locking mechanism inclosed in the said casing and carried by it and the valve stem and operating to prevent the unauthorized use of the valve.

3. The combination, with a casing having a valve seat at one end and a cover at the other, of a revoluble valve stem provided with a valve for closing the valve seat and having a screwthreaded portion which engages with a hole in the cover, and a locking mechanism inclosed in the casing and carried by it and the valve stem and operating to prevent the unauthorized use of the valve.

4. The combination, with a casing having a valve seat at one end and longitudinal grooves of predetermined length and depth at its middle part, of a valve stem provided with a valve for closing the valve seat and having also means for moving it longitudinally of the casing, and disks provided with lugs of predetermined different lengths for passing through the said grooves selectively, said disks being mounted in frictional engagement with the valve stem and operating to prevent the unauthorized use of the valve.

5. An apparatus as set forth in claim 4, the said disks and valve having spring devices mounted between them on the valve stem and pressing the disks longitudinally of the valve stem, and the said stem having a stop for receiving the longitudinal pressure.

6. An apparatus as set forth in claim 4, 120 the said casing having also a longitudinal stop rib on its other end portion from the valve seat, for placing the longer lugs of the disks in line with each other and arranging their shorter lugs out of line with each other prior to passing into the longitudinal grooves.

In testimony whereof I have affixed my signature.

HORTON H. HOBBS.
